United States Patent Office.

SAMUEL D. HOVEY, OF BROOKLYN, NEW YORK.

Design No. 4,904, dated May 16, 1871.

DESIGN FOR A RUBBER ERASER.

The Schedule referred to in these Letters Patent and making part of the same.

To all whom it may concern:

Be it known that I, SAMUEL D. HOVEY, of Brooklyn, in the county of Kings and State of New York, have invented certain Improvements in Design for Rubber Eraser, of which the following is a specification, reference being had to the accompanying drawing.

My invention relates to rubber erasers, and consists in the production of an eraser of a new and useful design or pattern, by which a large number of broad knife-edges is produced for the erasure of contiguous lines, as well as a number of flat surfaces for general use.

The shape, form, and pattern of my design for a

rubber-eraser are those of a star with long, broad, tapering points, as shown in the drawing, Figure 1.

It is made of rubber suitably prepared for the purpose, and in any of the known ways, with any desired number of broad tapering points, as shown, the whole forming the figure of a star, as shown.

Having thus described my invention—

What I claim is—

The design for a rubber eraser, as herein shown and described.

SAMUEL D. HOVEY.
